(57) **CLAIM**

The ornamental design for a can stand, as shown and described.

DESCRIPTION

FIG. 1 is a perspective view of a can stand showing our new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a left side elevation view thereof;

FIG. 7 is a right side elevation view thereof; and,

FIG. 8 is a perspective view thereof showing the can stand in an environment in which it may be used.

The broken lines in FIG. 8 show environment that forms no part of the claimed design.
